UNITED STATES PATENT OFFICE.

LITTLETON W. WALKER, OF ARLINGTON, VIRGINIA.

COMBINED WHEEL SCRAPER AND BRACE FOR WHEELBARROWS.

Application filed November 9, 1923. Serial No. 673,695.

This invention is an improvement in wheel scrapers for wheel barrows, and has for its principal object the provision of a wheel scraper which, though set out of contact with the wheel, will, upon the accumulation of material on the wheel, automatically remove the accumulation clear to the periphery of the wheel, and again return to its set position.

10 This I accomplish by fabricating the scraper of a resilient material, and positioning the blade of the scraper at such an angle to the wheel, and at such distance therefrom, that ordinarily, when the wheel is clear, it may turn out of engagement with the scraper, but upon an accumulation forming, such accumulation will engage with the blade as the wheel rotates, and if adhering tightly to the wheel, will bend the blade over 15 until it engages with the wheel, whereupon the continued rotation of the latter will cause the accumulation to be peeled or scraped off against the rear face of the blade. As soon as the accumulation is removed, the 20 blade will spring back to its set position.

A further object of the invention is to provide a wheel scraper that will also act as an efficient brace for the structure of the barrow. This is effected by increasing the 25 width of the blade toward the rear, until it approximates the width of the side rails of the barrow at the line of attachment, and bending over the rear part of the blade to lie against the under sides of the rails. The 30 bent over portion is punched to receive the bolts which secure the forward ends of the barrow legs to the rails. In this manner the bent over portion forms an adequate 35 brace for the barrow, as well as an anchor- 40 age for the blade, and by increasing the width of the blade toward the rear, and bending it with respect to the brace portion, the strength and resiliency of the blade is 45 materially increased.

With these and other objects in view which will become apparent as the description proceeds, the invention resides in the construction, combination and arrangement of parts hereinafter more fully described 50 and claimed, and illustrated in the accompanying drawings in which,—

Figure 1 represents a side elevational view of a wheel barrow, with the invention in place thereon.

55 Figure 2 represents a bottom plan view thereof, and

Figure 3 represents a view in perspective of the scraper and brace removed.

Referring more particularly to the drawings, the wheel barrow is of the usual construction, and includes the side bars 5 terminating at their rear ends in the handles 6, and upon which the body 7 is supported. The wheel 8 is mounted in the usual manner. The supporting legs 9 are secured at 60 their forward ends to the side bars by the use of bolts 10 as usual.

The combined blade 11 and brace 12 are formed integrally from a piece of resilient metal of suitable gauge. The blade is bent 70 with respect to the brace portion at such an angle that when the brace is in place across the side bars as shown, the blade will extend forwardly and downwardly toward the rear face of the wheel at an angle of approximately 45°. The forward narrower edge 13 of the blade does not normally bear against the wheel, but is spaced slightly therefrom, say an eighth of an inch, so that when the 75 wheel is clear of accumulation, it may turn 80 freely out of engagement with the blade.

Upon the formation of an accumulation upon the periphery of the wheel, such accumulation will, as the wheel revolves during the use of the barrow, in coming up 85 around the rear periphery of the path of the wheel, engage against the blade 11. If the accumulation is soft, or does not adhere 90 strongly to the wheel, the blade will bend only slightly toward the wheel, and the accumulation will be scraped off almost to the periphery of the wheel. It will be removed to such an extent as not to afford any appreciable retardation to the movement of the wheel. If, however, the accumulation is 95 hard, or of a stiff nature, or adheres closely to the wheel, it will, upon engaging with the lower edge of the blade 11, bend such blade in toward the periphery of the wheel, thereby bringing a wedging action into play, such 100 that will cause the accumulation to be scraped off against the rear face of the blade. The pressure of the accumulation against the blade will cause it to move closer and closer toward the wheel until it engages the 105 periphery thereof, and as the wheel continues to rotate, remove the accumulation clear to the periphery of the wheel. When the accumulation has been scraped or peeled off, the resiliency of the blade will bring it back 110 to its normally set position.

The openings 14 in the brace 12 for re-

ceiving the bolts 10, are so spaced as to allow the device to be attached to wheel barrows now in use, such attachment being effected by removing the nuts from the bolts 5 10, withdrawing these bolts, springing down the forward ends of the supporting legs 9, and placing the brace in position on the bolts. The forward ends of the supporting legs may then be again placed upon the 10 bolts, and the nuts tightened in place, thus securely binding the legs, brace, and side rails together. In order to further strengthen the brace, the rear edge thereof may be bent down or flanged as at 15. It 15 will, of course, be understood that the distance between the bolt openings in the brace may be varied, according to the distance apart of the bolts on the wheel barrows to which the device is to be applied.

20 I have found in actual use that a scraper and brace constructed according to my invention, not only effectively increases the stiffness and strength of the barrow structure, but operates admirably for the removal 25 of the accumulations, in the manner above set forth. Where barrows are used in cement working, or on roads where tar, sand and gravel are used, and in other work of a similar nature, the problem of keeping the 30 wheels clean is a serious one, so much so, that many contractors and gang foremen, at the end of the day's work, leave behind a man whose duty it is to clean the wheels of the wheel barrows by hand, so that upon 35 the resumption of activities the next day, the wheel barrows may be used without the annoyance caused by lumps of accumulation on the peripheries of the wheels. I have found in actual use that the scraper will at 40 all times keep the wheel clear, so that the use of my invention will do away with the requirement of manual labor for cleaning the wheels. It will also do away with the 45 practice now existing in many gangs, of hammering and banging the peripheries of

the wheel with shovels and hammers and spades, in order to clear them of accumulations. Obviously, such rough treatment is injurious not only to the wheel barrows, but to the other implements as well.

50 The foregoing detailed description has been given for clearness of understanding, and no undue limitations should be deduced therefrom, but the appended claims should be construed as broadly as permissible, in 55 view of the prior art.

I claim:—

1. The combination with a wheel barrow, of a brace rigidly connected to the side rails and extending transversely of the barrow, a 60 resilient blade formed integrally with the brace and extending downwardly and forwardly toward the wheel of the wheel barrow and terminating in spaced relation to said wheel, and adapted when engaged by an 65 accumulation on the wheel to have its free end moved under tension toward the wheel and when the accumulation is removed to spring back automatically to normal position, the blade being tapered toward its 70 forward end.

2. A wheel scraper including a brace portion having an integral flange along one side for rigidifying it, and an integral resilient blade portion along the other side bent 75 at an angle to the brace portion, the brace portion of such wheel scraper being adapted to be connected to the side rails of a wheel barrow, and the resilient blade portion being adapted to extend forwardly and downwardly toward the wheel of the barrow and terminate in spaced relation to such wheel and adapted when engaged by an accumulation on the wheel to have its free end moved under tension toward the wheel and 80 when the accumulation is removed to spring back automatically to normal position.

85 In testimony whereof I hereunto affix my signature.

LITTLETON W. WALKER.
